C. F. S. BILBROUGH

DETACHABLE FASTENER

Filed May 10, 1920

FIG.1.

FIG.2.

INVENTOR
CHARLES F. S. BILBROUGH

By J. H.

UNITED STATES PATENT OFFICE.

CHARLES FRANCIS STANHOPE BILBROUGH, OF BURNHAM-ON-CROUCH, ENGLAND.

DETACHABLE FASTENER.

Application filed May 10, 1920. Serial No. 380,351.

To all whom it may concern:

Be it known that I, CHARLES FRANCIS STANHOPE BILBROUGH, a subject of the King of Great Britain and Ireland, and a resident 5 of Burnham-on-Crouch, county of Essex, England, have invented a certain new and useful Improvement in Detachable Fasteners, of which the following is a specification.

- 10 This invention has reference to detachable fasteners for securing buttons, hooks, eyes and the like, and has for its object a more secure method of holding the same, while permitting of their release when desired.
- 15 The invention is adaptable to hooks and eyes, when the latter are provided with suitable vertical tongues or loops.

The fasteners to which the invention relates are of the kind comprising a loop 20 which resiliently holds together two legs extending from the loop, whereby the legs have a place of yielding engagement at the entrance to the loop, the device being so formed that the eye of the button may 25 be passed on to one leg, then pass the place of engagement, then round the loop, and then again past the place of engagement to a suitable retaining place beyond.

In the detachable fastener according to 30 the present invention, the legs of the loop are held resiliently together by the latter at two places of engagement, the one between the loop and an eye-retaining gap between the legs, and the other beyond the 35 gap, the leg on to which the button eye is passed from the loop being formed to restrain detachment of the button, as by being returned on itself to form a second loop and a second retaining gap acting in conjunction with the first one, and being 40 terminated by an enlarged end to serve as a stop. The beginning of the leg on to which the button-eye is first passed is conveniently bent into a hook-shape so as to readily enter 45 the eye of the button.

In order that my invention may be more readily understood, I have shown two embodiments of the same in the accompanying drawing, in which:

- 50 Figure 1 is a view of a complete fastener. Figure 2 is a view similar to Figure 1 showing a modification of the invention. Herein I provide a stem A constructed of springy or resilient metal, such as metal 55 wire, of oval section and of suitable size. One end of the stem I turn or bend round

in the form of a curved or angular loop or ring B (preferably curved as shown) and further bend the wire so as to engage or lie against the stem A, forming the resilient arm C which is provided at approximately its centre with the recess D. I may then bend the wire round in the form of a curve E. The extreme end F of curve E may be pointed so as more readily to enter the eye 60 of the button or the like.

The two parts of the resilient arm C which lie on each side of the recess D form projections G, H constructed to retain, when desired, the eye of the button in the recess D. The other end of the stem I bend to form an angular or curved bend, such as J, and the wire may then be further bent to lie parallel to and alongside the stem A, and be provided with the recess D¹ which is opposite recess D, and thus may form a second resilient arm similar to C, and for a like purpose. It may be provided with similar projections G¹, H¹, which act in conjunction with G, H in retaining the eye of the button on the stem A by confining this eye in the recesses D, D¹. The extreme end K is enlarged, flattened or so otherwise constructed as to prevent the eye of the button 70 passing over it. To permit the eye of the button being more readily passed round the ring B, I allow a suitable distance between the end K and the ring B as shown.

The operation of my device is as follows: The point F is passed through the eye of the button and the eye is then passed or threaded over the whole of the arm C round the ring B and past the projection G, on to approximately the central part of the stem A where it enters the recess D. It 90 may also enter the recess D¹ when two resilient arms are employed. The arms yield under pressure to permit of the button eye being passed under them, closing again 95 when the pressure is removed, so that when the said eye is in its normal position on the stem A, one or both of the sides of the eye is or are retained in the said recess or recesses until pressure is applied to pass it over the aforesaid projections.

Should the button eye be accidentally forced out of its normal position in the recess D or recesses D, D¹, and become threaded on the ring B or the curved part J, gravity tends to bring the device into 100 an approximately vertical position and thus tends to stop any further give in the resili-

ency of the device. The button eye cannot pass over the end K as explained.

I claim:

1. A detachable fastener of the class described consisting of a body wire bent to form a closed loop and the leg portions extending from the loop being disposed parallel, one of the same being provided with a keeper eye, said leg members both terminating in outwardly extending semi-circular portions, one of said semi-circular portions terminating in a penetrating point and the other of said portions terminating in a holding finger provided with a keeper recess.

2. A detachable fastener of the class described including a body wire having a straight portion formed at one end into a loop whereby the said body wire may be bent back upon itself to provide a portion parallel to the straight portion, and the said parallel portion having a keeper recess, and the ends of said parallel portions being

bent outwardly to form semi-circular portions, one of said semi-circular portions being provided with a penetrating point and the other being provided with a finger having a keeper recess adapted to be located opposite the keeper recess of the said parallel member.

3. A detachable fastener of the class described consisting of a body wire having its end portions bent to opposite sides thereof to provide leg members for resiliently engaging with opposite sides of the body wire, and both of said leg portions being provided with a laterally offset keeper eye forming portions registering at opposite sides of the body wire to receive a button loop and one of said leg members being provided with a penetrating point.

In testimony whereof I have hereunto affixed my signature this 17 day of April, 1920.

CHARLES FRANCIS STANHOPE BILBROUGH.
